UNITED STATES PATENT OFFICE.

LEWIS L. SCOTT, OF ST. LOUIS, MISSOURI.

DESIGN FOR A CASING FOR RADIATORS.

54,132.

Specification for Design.

Patented Nov. 4, 1919.

Application filed June 5, 1919. Serial No. 302,072. Term of patent 14 years.

To all whom it may concern:

Be it known that I, LEWIS L. SCOTT, a citizen of the United States, residing at the city of St. Louis and State of Missouri, have invented a new, original, and ornamental Design for a Casing for Radiators, of which the following is a specification, reference being had to the accompanying drawing, forming part thereof.

The figure is a perspective view of a radiator casing, showing my new design.

I claim:

The ornamental design for a casing for radiators, as shown.

LEWIS L. SCOTT.
